INVENTOR—

Parley R. Glass
By his Attorney
Nelson M. Morris

UNITED STATES PATENT OFFICE.

PERLEY R. GLASS, OF BROOKLINE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BOOT OR SHOE.

1,285,123.

Specification of Letters Patent. Patented Nov. 19, 1918.

Application filed December 15, 1915. Serial No. 66,948.

To all whom it may concern:

Be it known that I, PERLEY R. GLASS, a citizen of the United States, residing at Brookline, in the county of Norfolk and State of Massachusetts, have invented certain Improvements in Boots or Shoes, of which the following description, in connection with the accompanying drawings, is a specification, like reference characters on the drawings indicating like parts in the several figures.

This invention relates to improvements in boots and shoes and more particularly to the construction and arrangements of the eyelets of laced boots and shoes.

In shoes of certain styles it is desired to conceal the eyelets so that they shall not be seen when the shoe is laced upon the foot of the wearer. Heretofore eyelets have been set in the lining portion of the upper in register with a hole through the outer or leather part. It has been found that, under certain conditions and particularly in shoes where a light or soft leather is used in the upper, the strain upon the lacing pulls the hole in the leather part out of register with the eyelet set in the lining part, an occurrence which detracts greatly from the appearance of the shoe. An object of the present invention is to provide a construction and arrangement of eyelet which will obviate this difficulty without interfering with the systems of shoemaking and eyeleting employed at present by shoe manufacturers.

I have discovered that these results may be obtained by employing an eyelet having a continuous smooth flange and a barrel projecting from the flange having an elongated portion on one side, which may be clenched upon the outer surface of the leather part of the upper where it will be concealed by the lacing, and terminating throughout the remainder of its periphery below the surface of the leather part where its presence is partially concealed or rendered inconspicuous.

As herein shown the barrel of the eyelet is of noncircular cross section. Although not essential this construction is of great advantage in that it facilitates the handling of the eyelet and its presentation to the work with the elongated portion of the barrel accurately located in the proper position to be

clenched at the side of the eyelet toward the lacing slit. 55

Another feature of the invention consists in an eyelet having an elongated portion of its barrel clenched upon the outer surface of the outer part of the upper and the remainder of its barrel clenched upon the outer surface of the lining part. This arrangement is advantageous in that the eyelet is afforded a firm holding upon the material of the upper over an extended area.

These and other features of the invention will be best understood and appreciated from the following description of a preferred embodiment thereof selected for purposes of illustration and shown in the accompanying drawings, in which— 65 70

Figure 1 is a view in perspective of a portion of a shoe embodying the present invention;

Fig. 2 is a sectional view on an enlarged scale through one of the eyelets, and 75

Fig. 3 is a view in perspective of one of the eyelets as it appears before it is set in the upper.

The upper herein shown comprises an outer part 10, usually of leather, and a lining part comprising a stiffening strip of textile material 14 and an inner layer 12 of leather or textile material. 80

The eyelet comprises a flat flange 16 and a barrel 18 having at one side an elongated portion 20, the remainder of the barrel terminating in a plane parallel to the flange 16. The eyelet herein shown is of oval cross section, this being an advantageous shape because it facilitates handling of the eyelets and delivering them with the elongated portion of the barrel in a predetermined position. It is within the scope of the present invention to employ an eyelet of circular cross section although by so doing certain advantages incident to the assorting and delivering of oval eyelets would be sacrificed. 85 90 95

In setting the eyelets both the outer part 10 and the lining part 12, 14 are perforated and the eyelet is inserted from the inner side 100 of the lining part 12 so that its flange 16 rests upon the inner surface of said lining. It will be understood that the flange 16 of the eyelet is the smooth continuous flange of the eyelet as manufactured and, accordingly, the only part of the eyelet which con- 100 105

- tacts with the apparel of the wearer is entirely free of rough edges. The elongated portion 20 of the barrel projects entirely through both parts of the upper and is 5 adapted to be bent over or clenched upon the outer surface of the outer part 10 and upon the side of the lacing passage adjacent to the lacing slit. The remainder of the barrel is not sufficiently long to pass 10 through the outer part 10 of the upper but preferably is clenched upon the outer surface of the stiffening strip 14 of the lining part as shown in Figs. 1 and 2. The clenched elongated portion 20 holds together the 15 parts of the upper at the side of the lacing passage toward the lacing slit and the eyelet itself is thereby held in place. The remainder of the barrel being clenched upon the lining contributes still further to hold 20 the eyelet in place.

When the shoe is laced the lacing passes over the clenched elongated portion 20 of each eyelet and thus effectually conceals the parts of the eyelet which extend above the 25 outer part 10 of the upper. It will be apparent from an inspection of Fig. 2 that the pull of the lacing is transmitted entirely to that portion of the eyelet which engages both parts of the upper so that there is no 30 tendency to displace the leather part 10 with respect to the lining part 12, 14 or carry the hole in the leather out of register with the eyelet located beneath it.

Having thus described my invention, I 35 claim as new and desire to secure by Letters Patent:

1. A boot or shoe upper comprising an outer part and a lining part, both of said parts being perforated for a lacing, and eyelets set with their flanges upon the inner surface of the lining part and with their barrels clenched partly on the outer surface of the lining part and partly on the outer surface of the outer part.
- 40 2. A boot or shoe upper comprising outer and lining parts, and eyelets set with their flanges upon the inner surface of the lining part, one side of the barrel of each eyelet

extending entirely through the upper and being clenched on the outer surface thereof, 50 and the remainder of each barrel being clenched upon the outer surface of the lining part beneath the outer part.

3. A boot or shoe upper comprising outer and lining parts, and an eyelet clenched 55 with different portions of its barrel upon the outer surfaces of the respective parts.

4. A boot or shoe upper comprising outer and lining parts, and an oval eyelet having a smooth continuous flange and having one flat side of its barrel elongated and clenched upon the outer surface of the outer part, 60 said original, smooth, continuous flange being disposed on the inner surface of the lining part.

5. A boot or shoe upper comprising outer and lining parts both perforated for a lacing, and eyelets each comprising a barrel and a smooth, continuous flange, disposed with their original, smooth continuous flanges 70 against the inner surface of the lining part, the barrels of the eyelets, upon the side toward the lacing slit, being clenched upon the outer surface of the outer part and in the remainder of the barrel terminating below said surface.

6. A boot or shoe upper comprising outer and lining parts both perforated for a lacing, and eyelets disposed therein each comprising a continuous smooth flange, and a 80 tubular barrel projecting from the flange having an elongated portion on one side and terminating throughout the remainder of its periphery in a plane parallel to its flange.

7. A boot or shoe upper comprising outer and lining parts both perforated for a lacing, and eyelets disposed therein each comprising a continuous flange, and a tubular barrel of oval cross section projecting from the flange and having one of its flat sides elongated more than the remainder of the barrel.

In testimony whereof I have signed my name to this specification.

PERLEY R. GLASS.
